CLAIM

I claim the ornamental design for a telephone base unit, as shown and described.

DESCRIPTION

FIG. 1 is a front and top perspective view of a telephone base unit of the present invention;

FIG. 2 is a rear and top perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines show parts of the telephone base unit that represent unclaimed subject matter and form no part of the claimed design.

1 Claim, 8 Drawing Sheets
